UNITED STATES PATENT OFFICE.

WILLIAM SMITH HORRY, OF NIAGARA FALLS, NEW YORK, ASSIGNEE TO UNION CARBIDE COMPANY, OF NEW YORK, N. Y., A CORPORATION OF VIRGINIA.

ELECTRIC FURNACE.

1,130,734.

Specification of Letters Patent.

Patented Mar. 9, 1915.

Application filed January 21, 1914. Serial No. 813,534.

To all whom it may concern:

Be it known that I, WILLIAM SMITH HORRY, a subject of the King of Great Britain, residing at Niagara Falls, in the county of Niagara and State of New York, have invented certain new and useful Improvements in Electric Furnaces, of which the following is a specification.

My invention relates to electric furnaces and has for its object to obviate certain difficulties in the operation of such furnaces, and to provide an improved system of current delivery to such furnaces, whereby electrical losses are minimized, a high power factor obtained, and uniformity in power consumption maintained.

In my prior Patents 771,250 and 757,618, I have described the application of multi-phase currents to a furnace having a single hearth provided with a large number of electrodes. The present invention is an improvement on the systems of current distribution described in these prior patents, and consists, in addition to dividing the current supply to the furnace into many phases, in further sub-dividing the current in each phase into several portions each carried by its own conductor; in so arranging these conductors that each current portion is supplied to the corresponding electrode by different routes, along which flow currents of opposing sign; and in the particular arrangement of the conductors which deliver current from the bus-bars to the electrodes.

As a result of these improved arrangements, the self-induced voltage of the system, as a whole, is reduced because (1) the induction which would result from the passage of a large current through a small number of electrodes is diminished by the use of a large number of electrodes; (2) the induction is further diminished by using a multiplicity of conductors to each electrode, thereby lessening the amperage which has to be carried by any single conductor; (3) the induction is still further diminished by arranging these multiple conductors in such relation that each conductor is, as far as possible, surrounded by return conductors of opposing phase; and (4) by so arranging the conductors leading from the bus-bars to the electrodes as to minimize the induction at this point.

In the accompanying diagram, A represents the hearth of a six-phase electric furnace, preferably circular in shape, and having six electrodes, I, II, III, IV, V, VI.

T is a three-phase transformer having its secondary circuits connected to bus-bars, 1, 2, 3, 4, 5, 6, leading to the furnace. The transformer is of the "three-phase double delta" type, with its primary coils 7, 8, 9, connected as shown to the circuit 10, and its secondaries 71, 72, 81, 82, and 91, 92, connected to the bus-bars as shown.

Above the furnace are conductors arranged, as shown, in two deltas, one above the other, and constituting, in effect, two distinct systems connected only within the furnace by acting upon the common resistance there. The electrodes are connected to the bars of these deltas by cables 8, 8, 8.

The course of the current along the sets of bars 1, 2, 3, 4, 5, 6, can readily be followed by the arrows which are made long or short to represent the phase amplitude, the bars indicating the direction of the current. The inductive reactions which will take place between adjacent bars will also be readily apparent.

It will be noted that each electrode receives current from three sources, for example, electrode II receives current from the bars 2, 2, extending to the transformer T on the left-hand by way of the under delta, and from the third bar 2, extending directly to the transformer on the right-hand side; while the opposite electrode V receives current from two bars 5, 5, on the right-hand by way of the upper delta and from a third conductor connected directly to the transformer on the left-hand side. By this arrangement, the mutual inductance between the sets of bus-bars on both the right and left-hand sides can be largely neutralized.

It will be noted that the circuit connections in each delta are also arranged to minimize the self-induced voltage as far as possible, thus at the point Q in the lower delta, the 2-bar will be carrying one-third of the total current which is delivered through the electrode II while the 4-bar will be carrying current flowing in the same direction only one-sixth as large as the total current, since the return of the current delivered to the furnace through the electrode

2
 II, is divided between the electrodes IV and VI. The total self-induced voltage at this point is, therefore, only one-half of that which would be produced if a single conductor were carrying the total quantity of current. A similar condition would exist at the point R on the second leg of the delta, while at the point Z on the third leg whatever currents might be flowing in the two conductors would be in opposite directions and the induction therein would be neutralized. The total unneutralized induction would therefore, be that produced along the delta-shaped bars plus that in the short cables leading from these bars to the electrode. For example, with a current of 10,000 amperes at 60 cycles, there would be a self-induced voltage of about one volt per foot in the cables, but only one-half volt per foot along the legs of the delta. The induction in the bus-bars, interlaced in the manner shown, is practically negligible.

While I have shown three conductors leading to each electrode, it is obvious that the principle of dividing and subdividing the amperes and causing each portion of the current to arrive at the cables by different routes can be extended, and the inductive effects be, in this manner, still further reduced. It is also obvious that the same principle can be applied to furnaces having a smaller number of electrodes, and a smaller number of conductors carrying current to each electrode.

35 I claim:—

1. An electric furnace having a multiplicity of electrodes, means for supplying multiphase currents thereto, each of said electrodes receiving current of different phase from that of neighboring electrodes and by different routes from the source of current, each route being interlinked with others carrying currents of opposing phase.

2. An electric furnace having a multiplicity of symmetrically disposed electrodes, means for supplying multiphase currents thereto, each of said electrodes receiving current of different phase from that of neighboring electrodes and by different routes from the source of current, each route being

interlinked with others carrying currents of opposing phase.

3. An electric furnace having a plurality of electrodes, means for supplying multiphase currents thereto comprising a plurality of conductors in parallel for each phase leading to said electrodes, the conductors for each electrode extending thereto by different routes, each route being interlinked with others carrying current of opposing phase, whereby the self-induction of the system is minimized.

4. An electric furnace having a plurality of sets of electrodes, means for supplying to said electrodes a plurality of independent three-phase currents, each set of electrodes being delta-connected to its own supply.

5. An electric furnace having a plurality of sets of electrodes, means for supplying to said electrodes a plurality of independent 3-phase currents, each set of electrodes being delta-connected to its own supply, a plurality of conductors in each phase, said conductors being interlinked with others carrying current of opposing phase.

6. An electric furnace having a plurality of sets of electrodes, three electrodes in each set, means for independently supplying 3-phase current to each set, said means comprising a plurality of conductors in each phase, all the conductors leading from the sources of supply to the furnace being interlinked with others carrying current of opposing phase.

7. An electric furnace having a plurality of sets of electrodes, three electrodes in each set, means for independently supplying 3-phase current to each set, said means comprising a plurality of conductors in each phase and delta-connected to the electrodes, the conductors for each delta being interlaced with opposing phase current-carrying conductors of another delta.

In testimony whereof, I affix my signature in presence of two witnesses.

WILLIAM SMITH HORRY.
